UNITED STATES PATENT OFFICE.

JOHN S. WILLIAMSON AND HERBERT L. BEACH, OF BALTIMORE, MARYLAND, AS-SIGNORS, BY DIRECT AND MESNE ASSIGNMENTS, TO SIDNEY L. DAVIS, RECEIVER FOR MORGAN MANUFACTURING COMPANY, INC., OF KEENE, NEW HAMPSHIRE.

DESIGN FOR A VEHICLE PARKING-LIGHT CASING.

Application filed April 14, 1924. Serial No. 9,272. Term of patent 3½ years.

To all whom it may concern:

Be it known that we, JOHN S. WILLIAMSON and HERBERT L. BEACH, both citizens of the United States of America, residing at the city of Baltimore, State of Maryland, have invented a new, original, and ornamental Design for a Vehicle Parking-Light Casing, of which the following is a specification, reference being had to the accompanying drawings, forming part thereof.

In the drawings:

Fig. 1 is a side elevation of the vehicle parking light casing embodying our invention.

Fig. 2 is a front elevation.

What we claim is:

The ornamental design for a vehicle parking light casing, substantially as shown.

Signed at Baltimore, State of Maryland, this 11th day of April, 1924.

JOHN S. WILLIAMSON.
HERBERT L. BEACH.
